UNITED STATES PATENT OFFICE.

EDWARD SCHINDLER, OF EASTON, PENNSYLVANIA.

SASH-FASTENER.

SPECIFICATION forming part of Letters Patent No. 686,345, dated November 12, 1901.

Application filed May 7, 1900. Serial No. 15,700. (No model.)

To all whom it may concern:

Be it known that I, EDWARD SCHINDLER, a citizen of the United States, residing at Easton, in the county of Northampton, in the 5 State of Pennsylvania, have invented certain new and useful Improvements in Sash-Fasteners, of which the following is a full, clear, and exact description, reference being had to the accompanying drawings, forming a part 10 of this specification.

This invention relates to sash-fasteners; and it has for its object to provide a simple and efficient construction in which the bolt of the fastener may be locked and unlocked 15 by means of a suitable key.

To this end the invention, as generally stated, comprises a plate or support, a bolt thereon, and an independently-movable key-controlled locking and unlocking device for 20 said bolt.

It also comprises certain novel features of construction and arrangement of parts, which will be hereinafter described and claimed.

In the drawings, Figure 1 is a front elevation of a window having my improved fastener applied thereto. Fig. 2 is a horizontal section as on the line 2 2 of Fig. 1, the key being included. Fig. 3 is a vertical section as on the line 3 3 of Fig. 1. Fig. 4 is a perspective view of the device detached. Fig. 30 5 is a front view thereof.

A' represent the upper and lower sashes, respectively, of a window, and B represents my improved fastener applied thereto. The 35 upper rail of the lower sash is horizontally slotted or mortised to receive the bolt and adjuncts of the fastener, while the meeting-rail of the upper sash is provided with a slotted keeper b, with which the bolt is adapted 40 to coat. This bolt comprises the longer arm b' of a bell-crank lever fulcrumed between inwardly-extending lugs b² on a plate b³, which is secured by screws b⁴ or other means to the inner side of the sash-rail. The plate 45 is longitudinally slotted, as at b⁵, to receive the shorter arm b¹¹ of the lever, the free end of such arm being provided with an outwardly-extending knob or thumb piece b⁶, by means of which the lever may be manipulated 50 so as to engage the arm b' thereof with or disengage it from the keeper b on the adjacent

sash. The end of the arm b¹¹ is provided with a suitably-located notch b⁷, into and from which the free end of a dog or latch b⁸ on the inner face of the plate may be moved when the bolt is engaged with the keeper. The 55 pivot-pin b⁹ of the dog extends outwardly through the plate and is triangular, square, or other appropriate shape in cross-section for engagement by a suitable key C, whereby the 60 dog may be swung up or down to disengage it from or engage it with the notch in the lever, as desired. This extension of the pivot-pin is laterally incased by a barrel or guard b¹⁰, formed on the outer side of the base, so 65 that the dog cannot be manipulated without the use of an appropriate key that may be inserted in the barrel and engaged with the pivot-pin.

It will be obvious that the body of the fastener may be applied to the side of one of the 70 sashes and the adjoining side piece of the other sash be provided with a suitably-located keeper for engagement by the bolt of the fastener.

My invention is not restricted to the particular details of construction herein shown and described, as the same may be variously modified without departing from the fair 75 spirit of the invention.

I claim—

1. In a sash-fastener, a plate provided with an outwardly-extended barrel and adapted to be secured to one of the meeting-rails of a sash, a bell-crank or angular lever on one 85 side of said plate, one arm of which lever constitutes a locking-bolt, the other of said arms being extended through the plate and provided with an operating handle or knob, a pivoted locking-dog on one side of said plate 90 adapted to engage with one of the arms of the said bell-crank lever, the pivot-pin on the said dog being extended within said barrel and adapted to be engaged by a suitable key for operating the dog.

2. A sash provided with a recess in one of the rails thereof, a plate having an outwardly-extended barrel, a bell-crank or angular lever pivoted on said plate within said recess of the sash-rail, one arm of said lever being extended through the plate and provided with a handle or knob, a pivoted locking-dog on 95 100

the inner side of said plate, the meeting-rail of the opposite sash being provided with a recess, and a key to engage the pivot of the dog to hold the bell-crank lever in locking position and in engagement with the last-named recess.

5 In testimony whereof I have hereunto af-

fixed my signature in the presence of two subscribing witnesses.

EDWARD SCHINDLER.
